UNITED STATES PATENT OFFICE

MANFRED von ARDENNE, OF BERLIN, GERMANY, ASSIGNOR TO RADIO CORPORATION OF AMERICA, A CORPORATION OF DELAWARE

RADIO RECEIVING CIRCUIT

Application filed November 11, 1926, Serial No. 147,656, and in Germany October 21, 1925.

An application for patent for this invention has been filed in Germany, on October 21, 1925.

This invention relates to a receiving arrangement and more particularly to an arrangement wherein a resistance coupled amplifier is used for both radio and audio frequency amplification.

Although, as has been found by research of the applicant, the most favorable conditions for attaining effective amplifications with the use of the so-called potential amplifier principle are not the same for radio frequency and audio-frequency currents, it has also been discovered that resistance-coupled radio frequency amplifiers allow of an amplification, as hereinafter described, which results in a substantial improvement in the conditions of reception, and their use insures a saving in the first cost of efficient receiving apparatus.

The so-called reflex principle in connection with the ordinary type of amplifier tube is well known. That is, the tube can be employed for the simultaneous amplification and rectification of radio frequency currents and for the reflection and renewed amplification of the resultant low frequency impulses. However, while radio frequency amplifiers are usually worked with tuned radio frequency circuits or choke coils, it has of late been possible to build radio frequency amplifiers with purely ohmic resistances allowing of an efficient radio frequency potential amplification down to very short waves. Although such resistance-coupled radio frequency amplifier tubes fail to give at the same time most favorable conditions for the amplification of low-frequency currents, it is nevertheless true that their amplifying power is sufficient for all practical purposes.

It is an object of this invention to use such a resistance-coupled potential amplifier tube, in conformity with the reflex principle, for the amplification of the ensuing low frequency impulses, without incidentally impairing its radio frequency amplifying powers. With a single multi-stage resistance-coupled radio frequency amplifier it is thus feasible to attain particularly good receiving action. As

it were, the whole resistance-coupled radio frequency amplifier can be treated as a single receiver tube, and, according to the reflex principle, the incoming energy, changed into low frequency energy either by the amplifier itself or by a separate detector, is again passed through the resistance coupled radio frequency amplifier arrangement as a whole, with the result that renewed and considerable amplification of the low-frequency energy is obtained without an incidental impairment of the radio frequency amplifier action. The receiving effects thus attained without the use of radio frequency back-coupling are especially favorable. By such double use of the resistance-coupled amplifier it is feasible, for instance, to raise signals, which after simple radio frequency amplification and rectification are just audible, by renewed low frequency amplification in the same amplifier to a strength adequate for loud speaker operation.

Another object of this invention is to provide a receiving arrangement wherein only a single audio transformer is necessary for reflexing in a multi-stage amplifier.

Heretofore it was necessary that such a transformer be used with each amplification stage, but with the circuit herein disclosed, the need for a plurality of audio frequency transformers has been dispensed with.

The operation of the receiving arrangement according to this invention is diagrammatically illustrated in the drawing.

The radio frequency energy picked up by an open antenna or by a loop or coil antenna 1, preferably after having been tuned, is fed by means of a coupling 1' through circuit 2 to the grid 3 of the first stage of the resistance-coupled radio frequency potential amplifier.

Numerals 4, 5, 6 designate the filaments of three tubes numbered 4', 5', and 6' respectively which are heated from the battery 7. 8 is the plate battery; 9 and 10 are high-ohmic plate resistances; 11, and 12, are grid leaks; while 13 and 14 are coupler condensers. In the output circuit of the third amplifier stage there is inserted an anti-resonant circuit 15 tuned to radio frequency. The coil 15' of 100

circuit 15 is coupled to a coil 16', and the output from the latter is rectified, for instance, by a crystal or tube detector 16.

But the signal heard in the telephone receiver 17 is small. However, if an audio frequency transformer 18 is inserted in the detector circuit 16, and if the low frequency energy is again fed to the grid circuit of tube 4' through the leads 20, 21, then the low frequency energy will be efficiently amplified by the resistance coupled potential amplifier. The amplified audio frequency currents are utilized in any well known manner, as by a loud speaker 19 inserted in the plate circuit of the tube 6'.

In the use of the reflex principle as herein-before described, the telephone receiver 17 in the detector circuit may, of course, be dispensed with since the loud-speaker in the plate circuit of the third tube takes the place of the telephone.

What may be emphasized as a special feature of the present invention when contrasted with the well known reflex circuit arrangements is that by the method disclosed in this invention it is possible for the first time to utilize all of the tubes for low frequency reflex effects. In the reflex connections heretofore disclosed, this has not been possible for the reason that ordinarily at least one tube of the arrangement was arranged so as to be suited only for radio frequency amplification, in other words, only one coil of a few turns for example, was inserted in the plate circuit, or a tuned oscillation circuit. Hence, the low frequency reflex action according to the present invention allows a more efficient utilization of the existing tube equipment than has been true of reflex circuit arrangements heretofore used.

I claim as my invention:

1. In a receiving circuit, a multi-stage resistance coupled radio frequency amplifier, means including a tuned circuit for controlling the input to said amplifier, a system tuned to radio frequency in the output circuit of the end stage of said amplifier, and means coupled to the tuned system including a single audio frequency transformer and a crystal detector for reflexing the audio output of the end stage of said resistance coupled amplifier through said resistance coupled amplifier.
2. In a radio signalling system an antenna, a multi-stage resistance coupled amplifier, means for coupling said amplifier to said antenna, a tuned circuit in the output circuit of the end stage of said amplifier, and means coupled to the tuned circuit and including a contact rectifier for reflexing the audio frequency output of the end stage of said amplifier into the first stage of said amplifier.

MANFRED VON ARDENNE.
